UNITED STATES PATENT OFFICE.

HENRY ALLEN AVERY, OF GROTON, NEW YORK, ASSIGNOR TO CORONA TYPEWRITER COMPANY, INC., OF GROTON, NEW YORK, A CORPORATION OF NEW YORK.

TYPEWRITING MACHINE.

Application filed March 31, 1923. Serial No. 629,091.

This invention relates to improvements in typewriting machines, and has for its principal objects to provide a machine in which useless operation of the ribbon-feeding and vibrating mechanism when the space-bar is operated is avoided, thus eliminating unnecessary wear and noise and relieving the operator of unnecessary labor; to provide simple and efficient letter-feed mechanism in which provision is made for operating the escapement from the printing keys and from a space-bar by independent sets of operating connections; to provide adjustable space-bar-operated means for actuating a dog rocker, whereby the rocker may be moved equal distances by the space bar and universal bar; to provide simple and efficient space-bar-operated means for operating a dog-rocker which shifts with a platen-carriage and its support when changing case; and to provide a compactible machine having separable connections between a dog-rocker on one frame part and a space-key mechanism and a universal bar mechanism on another frame part, which connections are automatically broken and restored by movement of one frame part relatively to the other.

Other features and advantages will appear from the following description of the preferred embodiment of the invention illustrated in the accompanying drawings.

In the drawings.

Figure 1 is a vertical longitudinal sectional view of a typewriting machine embodying the present improvements;

Fig. 2 a detail sectional view showing the platen carriage and shift frame elevated to their uppermost or "fig." shift position;

Fig. 3 a detail sectional view showing the foldable frame part swung partly toward compacted position;

Fig. 4 a perspective view of the letter feed mechanism and the space-bar-operated means for actuating the same;

Fig. 5 a perspective view showing the case-shift means, the space-bar mechanism, and the universal bar with part of the mechanism operated thereby for feeding and vibrating the ribbon as well as the dog-rocker

operating means controlled by the universal bar;

Fig. 6 a detail sectional view on the line 6—6 of Fig. 1; and

Fig. 7 a perspective view of the ribbon vibrating mechanism.

The improvements are shown embodied in a Corona (model 3) typewriting machine, and only so much of said machine as is necessary to a full and clear understanding of the invention is therefore shown and described. The platen carriage 1 with the platen 5 thereon travels on bearings on the carriage bed 2, the carriage being normally urged in letter-feed direction by the usual spring drum and draw-band which are not shown. An escapement rack 3 is secured to the carriage. The bed 2 is rigidly secured on the rear ends of the folding arms 4 pivotally held at 6 at their forward ends to the two forwardly extending, vertically shiftable, frame bars 7. Bars 7 are rigidly held adjacent their rear ends to the upper ends of the two vertically shiftable posts 8 which are slidably guided in brackets 9 mounted in the rear of the main or base frame part 10 of the machine near opposite sides of the machine. The lower ends of posts 8 are connected by a rod 11 which is guided vertically in slots 12 in brackets 13 mounted on frame part 10, the posts and rod being secured to each other by screws 14.

A dog rocker 15 which, except for the arm or extension 16 hereinafter described, is of the same construction as in the Corona machine, is pivotally held by a pivot screw 17 to the carriage bed to rock transversely of rack 3, said screw passing through a hole in boss 18 on the rocker. The step-by-step letter-feed movement of the rack and carriage is controlled by the usual rigid and limber dogs 19 and 20, respectively, the rocker 15 being normally held by spring 27 with its inner end engaging the rear face of an abutment 22 on a bracket 23 held to the carriage bed, in which position the limber dog 20 engages with the rack.

The dog rocker finger 24 is adapted to be engaged by a tappet 25 on the cross-bar of a fore-and-aft rocking frame 26

whenever a type key is depressed to move the inner end of the dog rocker rearwardly and thus disengage dog 20 and engage dog 19 with the rack. The drop or feed 5 takes place as usual on the upstroke of the key on the return movement of the dog rocker by spring 27 the forward end of which is held to a bracket 28 on the carriage bed which supports part of the rib- 10 bon vibrating means. The depending arms of frame 26, which is of inverted U-shape, are pivotally held to rod 11 at the inner faces of brackets 13, and said arms are pro- 15 vided with vertical slots 29 in which fingers 30 on the upper ends of levers 31 engage in all case shift positions of the carriage. Levers 31 are connected at their upper ends by a transverse bar 32 and are pivotally held by screws 33 to brackets 9 to swing 20 fore-and-aft of the machine. Links 34 connect the lower ends of levers 31 with the forwardly extending side arms of a U-shaped universal bar 35, which arms are pivoted on one of the transverse key-lever 25 pivot rods 36 rigidly held to brackets 37 at the sides of frame part 10. The trans- 30 verse member of the universal bar extends over the rear ends of all the printing key levers 38 and is adapted to be rocked up- 35 wardly against the tension of a spring 39 by either of said key levers to force frame 26 and tappet 25 rearwardly to actuate the dog rocker 15. The return movement of the frame 26 is limited by engagement of the tap- 40 pet with a rod 40 connecting frame bars 7. The ink ribbon 41 is wound on spools 42 held to spindles 43 on posts 44 secured to folding arms 4, said spools being rotated by worm gears 45 on the spindles meshing 45 with worms 46 fixed on shafts 47 journalled in brackets on arms 4. Shafts 47 carry ratchet wheels 48 rotated by pawls 49 piv- 50 oted at 50 on frame 26. The ribbon vibra- 55 tor 51 is pivoted at 52 on bracket 28 on the bed 2 and is connected at its inner end to the ribbon guide 53 slidably held to a bracket 54 fixed on the carriage bed. Vibra- 60 tor 51 is actuated by a horizontally swing- 65 ing oscillating means 55 rocked by a finger 56 on frame 26, said finger engaging in a slot in the oscillating device (see Fig. 7) and rocking said device about its pivot 57 on bracket 28 against the tension of a spring 58.

55 The frame parts 4, 7, 8 and 11, and the devices mounted thereon, are vertically shiftable to vary the relation between the platen 5 and the type bars 59 which are pivoted in a segment 60 mounted on frame 60 part 10 and connected with key levers 38 by links 61. To shift said parts a rock shaft 62 journalled at its ends on frame part 10 is provided, said shaft having a rock arm 63 at one end connected with rod 11 and 65 having a "fig." shift key-lever 64 rigid-

ly held thereto adjacent the other end thereof, the rear end of key lever 64 being also connected to rod 11. A "cap." shift key lever 65 is loosely pivoted on a reduced part 66 of shaft 62 and is not connected at its rear end with rod 11, said lever, however, being in the Corona machine formed with a cam at its rear end to operate a "cap." shift stop device, not shown. Key- 70 lever 65 is formed with a lug 67 engaging under the rear arm of lever 64 to operate the shift mechanism through the medium of lever 64. A return spring 68 is provided for lever 65.

The foregoing parts with the exception 75 of the dog rocker are all constructed and operate as in the Corona machine referred to. The improvements will now be de- 80 scribed. The space-bar 69 is supported on the forward ends of two spacing levers 70 rigidly affixed to a rock shaft 71 journalled at its ends in bracket 37, one of said levers 85 having a rearwardly extending stop arm 70^a carrying a sleeve-like rubber bumper 72 at its rear end normally held resting on top 90 of rock-shaft 62 of the case-shift mechanism by a space bar return spring 73 which is connected at its ends with arm 70^a and a bar 74 mounted on brackets 37. An up- 95 standing sheet metal rock arm 75 is rigidly 100 affixed at its lower end to rock shaft 71 adjacent the left hand side of base frame part 10, said arm being formed at its upper end with a rearwardly and downwardly extending portion 75^a bendable fore-and- 105 aft of the machine for purposes of adjust- 110 ment. Portion 75^a is sufficiently stiff to re- main in the adjusted position to which it may be bent. A rigid pull and push link 115 76 formed of stiff wire is formed with hook 120 ends 77 passed through an aperture in the lower end of portion 75^a of arm 75 and an aperture substantially midway the ends of 125 an upstanding sheet metal rock arm 78. Link 76 is thus pivotally held at its ends 130 to the two upstanding rock arms and nor- mally preferably extends slightly downward from its forward to its rear end.

Rock arm 78 extends up alongside the in- 135 ner face of left-hand frame bar 7 and is 140 formed with a forwardly extending ear 79 at its upper end provided with a forwardly and downwardly turned guide slot 80 through 145 which passes the shank of a retaining and guiding screw 81 between the head of which and bar 7 said ear 79 is slidably confined. Screw 81 holds rock arm 78 against lateral 150 and vertical movements at its upper end, while permitting said arm to rock about its 155 pivotal support on rod 11 of the shift frame, and also prevents accidental disconnection of the rock arm from its pivot. In the con- 160 struction shown the lower part of rock arm 78 is offset toward the left of the upper part 165 to carry the lower end of the rod outside of 170

the adjacent post 8, the upper and lower parts of said rock arm being connected by a downwardly and outwardly inclined portion 78^a. Rock arm 78 is formed with a forked 5 lower end 78^b, the legs of which extend downwardly at opposite sides of the elongated head of screw 14 and engage in a circumferential groove 82 in the screw head. Arm 78 is thus detachably and pivotally held 10 to the shift frame to move up and down therewith and rock fore-and-aft relatively thereto, and is held against lateral movement at both ends.

At its upper end rock arm 78 is formed 15 with a rearwardly extending finger 83 formed with an inwardly turned rear end part or hook 84 loosely engaging the rear edge of arm 16 of the dog rocker 15 at the left side of pivot screw 17. Finger 83 is off- 20 set inwardly as shown to clear post 8, and it will be obvious that when space bar 69 is depressed said finger will pull arm 16 of the dog rocker forward, thus moving the inner or main dog-carrying body part of the 25 rocker rearwardly. When the space bar is released spring 73 will restore the space bar and rock arms 75 and 78 and link 76 to their normal position which is determined by the stop arm 70^a which engages shaft 62. It will 30 thus be obvious that an actuation of the space bar will cause an operation of the escapement, the drop or feed taking place on the return stroke of the space bar. By bending part 75^a the arm 78 may be adjusted for- 35 wardly or rearwardly as may be necessary to cause the same to properly act upon the dog rocker.

During case-shifting arm 78 moves with the shiftable frame part and maintains its 40 operative relation with the dog rocker in all three case-shift positions of the platen. Link 76 swings about its forward pivoted connection 77 with arm 75 during case-shift movements, and its rear end moves from a normal 45 lower-case position below the plane of said forward pivot to an extreme "fig." shift position above the plane of said pivot.

When the machine is compacted by swing- 50 ing arms 4 forwardly through an arc of 180 degrees to place the carriage in an inverted position over the keyboard, the operating train between the printing keys and the feed-dogs of the escapement separates automatically, finger 24 of the dog rocker moving 55 away from tappet 25 on rocking frame 26, while the ribbon feed operating chain separates by movement of ratchets 48 away from feed pawls 49 on the rocking frame 26, and the ribbon vibrator operating chain sepa- 60 rates by movement of oscillator means 55 away from finger 56 on frame 26, all as in the Corona machine. The operating chain between the space bar and feed dogs is broken during compacting the machine, by mov- 65 ment of arm 16 of the dog rocker away from

hook end 84 of finger 83 on rock arm 78, and all four of the separable operating chains referred to are automatically restored upon swinging the platen carriage and its pivoted support back to their normal position. 70

What I claim is:

1. In a typewriting machine, the combination of a platen carriage, a carriage support hinged to fold to a compact inverted position over the keyboard of the machine, 75 an escapement dog rocker extending transversely of the machine, means pivotally supporting said dog rocker intermediate its ends on the carriage support to swing horizontally, a universal bar, means operated by 80 the universal bar for pushing rearwardly against said dog rocker at one side of its pivot, a space bar, and means operated by the space bar for pushing forwardly on the dog rocker at the opposite side of its pivot, 85 both said rocker pushing means having a loose abutting engagement only with the rocker.

2. In a typewriting machine, the combination of a main frame, a carriage shift frame, 90 a platen carriage on said shift frame, escapement mechanism for the carriage including a dog rocker pivotally supported on said shift frame, printing instrumentalities mounted on the main frame, a universal bar 95 pivotally mounted on the main frame operable by the printing instrumentalities, ribbon vibrating means operable by said universal bar, a space bar pivotally mounted on the main frame, a pair of independent 100 actuators mounted on the shift frame and each arranged to operate the dog rocker without imparting motion to the other actuator, means connecting the universal bar with one of said actuators for operating the 105 actuator in all case positions of the shift frame, and means independent of said last-mentioned means connecting the space bar with the other actuator for operating said actuator in all case positions of the shift 110 frame.

3. In a typewriting machine, the combination of a platen carriage, a support for the carriage, a feed-dog rocker, means pivotally holding the rocker to the support, a 115 main frame, printing instrumentalities mounted on the main frame, means operated by the printing instrumentalities for actuating the dog rocker, a space bar, independent means operated by the space bar for actuating the dog rocker, and case-shift means for shifting the carriage support relatively to the main frame, both of said dog-rocker actuating means having relatively shiftable parts mounted on the main frame and the 120 carriage support, said carriage support comprising a frame part movable by the case shift means carrying the shiftable parts of the dog rocker actuating means and a frame 125 part carrying the platen carriage and dog 130

rocker and connected with the shiftable frame part to shift therewith to change case and to fold relatively thereto to compact the machine, said dog rocker moving into and out of cooperative relation with its actuating means automatically when the machine is extended and compacted.

4. In a typewriting machine, the combination of a main frame, printing instrumentalities on the main frame, a platen carriage, a support for the carriage shiftable relatively to the main frame to compact the machine, a universal bar on the main frame operable by the printing instrumentalities, a ribbon vibrator and ribbon spools on the shiftable support, an escapement dog rocker on the shiftable support, separable operating connections between the universal bar and said ribbon vibrator and spools and dog rocker, a space bar on the main frame, and means forming a separable operating connection between said space bar and dog rocker wholly independent of the connection between the universal bar and dog rocker.

20 5. In a typewriting machine, the combination of a main frame, printing instrumentalities on the main frame, a platen carriage, a support for the carriage shiftable relatively to the main frame to compact the machine, a universal bar on the main frame operable by the printing instrumentalities, a ribbon vibrator and ribbon spools on the shiftable support, an escapement dog rocker on the shiftable support, separable operating connections between the universal bar and said ribbon vibrator and spools and dog rocker, a space bar on the main frame, means forming a separable operating connection between said space bar and dog rocker wholly independent of the connection between the universal bar and dog rocker, and key-operated case-shift means on the main frame for moving the carriage support and dog rocker and a part of each of said separable operating connections in unison without disconnecting the separable parts of the several connections.

6. In a typewriting machine, the combination of a platen carriage, a case-shift frame for the carriage, key-operated means for shifting said shift frame, a main frame, printing instrumentalities, a dog rocker shiftable with the platen carriage, a rock arm mounted on the shift frame to shift therewith and connected to operate the dog rocker, a space key on the main frame, means operable solely by said space key for rocking said arm relatively to the shift frame in all case positions of the shift frame, a universal bar mounted on the main frame operable solely by the printing instrumentalities, and means operated by the universal bar for actuating the dog rocker in all case positions of the shift frame.

55 7. In a typewriting machine, the combi-

nation of a platen carriage, a case-shift frame for the carriage, key-operated means for shifting said shift frame, a main frame, printing instrumentalities, a dog rocker shiftable with the platen carriage, a rock arm mounted on the shift frame to shift therewith and connected to operate the dog rocker, a space key on the main frame, means operable solely by said space key for rocking said arm relatively to the shift frame in all case positions of the shift frame, and means operable solely by the printing instrumentalities for actuating the dog rocker in all case positions of the shift frame, said last-mentioned means comprising constantly connected relatively shiftable parts mounted on the main frame and shift frame respectively.

8. In a typewriting machine, the combination of a main frame, a platen carriage, a vertically shiftable support for the carriage, an escapement dog rocker pivotally held to said support intermediate its ends to swing horizontally and extending transversely of the machine, key-operated printing instrumentalities on the main frame, a universal bar on the main frame operable by the printing instrumentalities, means on the shiftable support operable by the universal bar adapted to engage the forward edge of the dog rocker at the inner side of its pivot and push the inner end of the rocker rearwardly when a printing key is depressed, a space-bar on the main frame, means on the shiftable support operable by the space bar adapted to engage the rear edge of the dog rocker at the outer side of its pivot and push the outer end of the rocker forwardly when the space bar is depressed, a rack on the carriage, feed dogs on said rocker cooperating with said rack to control letter-feed movements of the carriage, and shift-key-operated means for shifting the carriage support vertically.

9. In a typewriting machine, the combination of a main frame, a platen carriage, a vertically shiftable support for the carriage, an escapement dog rocker pivotally held to said support intermediate its ends to swing horizontally and extending transversely of the machine, key-operated printing instrumentalities on the main frame, a universal bar on the main frame operable by the printing instrumentalities, means on the shiftable support operable by the universal bar adapted to engage the forward edge of the dog rocker at the inner side of its pivot and push the inner end of the rocker rearwardly when a printing key is depressed, an upstanding rock arm pivotally held to the shiftable support at its lower end and engaging behind the dog rocker at the outer side of the pivot of said rocker, a rock shaft journaled on the main frame, an upstanding rock arm rigidly held on said shaft at its lower end, a

rigid link connecting said upstanding rock arms, spacing levers rigidly held to said rock shaft, a space bar supported on said levers, and shift-key-operated means for shifting the carriage support.

10. In a typewriting machine, the combination of a main frame, a platen carriage, a vertically shiftable support for the carriage, an escapement dog rocker pivotally held to said support intermediate its ends to swing horizontally and extending transversely of the machine, key-operated printing instrumentalities on the main frame, a universal bar on the main frame operable by the printing instrumentalities, means on the shiftable support operable by the universal bar adapted to engage the forward edge of the dog rocker at the inner side of its pivot and push the inner end of the rocker rearwardly when a printing key is depressed, an upstanding rock arm pivotally held to the shiftable support at its lower end and engaging behind the dog rocker at the outer side of the pivot of said rocker, a rock shaft journaled on the main frame, an upstanding rock arm rigidly held on said shaft at its lower end, a rigid link connecting said upstanding rock arms, spacing levers rigidly held to said rock shaft, a space bar supported on said levers, shift-key-operated means for shifting the carriage support, and a return spring connected with one of said spacing levers for restoring the rock arms and space bar to normal position.

11. In a typewriting machine, the combination of a main frame, a platen carriage, a vertically shiftable carriage support, an escapement dog rocker pivotally mounted on the shiftable support, a space bar, levers supporting said space bar at their forward ends, a transverse rock shaft mounted on the said frame to which the levers are rigidly held, an upstanding rock arm rigidly held at its lower end to said rock shaft, an upstanding dog rocker actuator at the rear of said rock arm loosely engaging behind a part of the dog rocker, means pivotally supporting said actuator at its lower end on the shiftable support to swing fore and aft of the machine, and a link connecting the rock arm and actuator.

12. In a typewriting machine, the combination of a pivotally supported escapement-dog rocker, a space bar, levers supporting said space bar at their forward ends, a transverse rock shaft to which the levers are rigidly held, an upstanding rock arm rigidly held at its lower end to said rock shaft, an upstanding dog rocker actuator at the rear of said rock arm loosely engaging the dog rocker, means pivotally supporting said actuator at its lower end to swing fore and aft of the machine, a link connecting the rock arm and actuator, one of said levers extending rearwardly beyond the rock shaft, a

spring connecting the rearwardly extended arm of said lever with the machine frame and normally tending to pull said arm downward, and means on the machine frame under said arm of the lever for limiting the downward movement of said lever arm.

13. In a typewriting machine, the combination of a pivotally supported escapement-dog rocker, a space bar, levers supporting said space bar at their forward ends, a transverse rock shaft to which the levers are rigidly held, an upstanding rock arm rigidly held at its lower end to said rock shaft and having a rearwardly and downwardly turned part at its free end bendable fore and aft of the machine, an upstanding dog rocker actuator at the rear of said rock arm loosely engaging the dog rocker, means pivotally supporting said actuator at its lower end to swing fore and aft of the machine, and a link connecting the bendable part of the rock arm and actuator.

14. In a typewriting machine, the combination of a main frame, a shift frame, a platen carriage on the shift frame, escapement mechanism for the carriage including a dog rocker pivoted on the shift frame, ribbon vibrating mechanism, a universal bar mechanism for actuating the dog rocker and ribbon vibrating mechanism, a space bar, levers extending fore and aft of the main frame and supporting said space bar at their forward ends, a rock shaft to which said levers are fixed journaled on the main frame and extending transversely of said frame, an upstanding rock arm fixed on said shaft at its lower end, an upstanding dog rocker actuator pivotally mounted at its lower end on the shift frame to the rear of said rock arm and loosely engaging the dog rocker, a link connecting the rock arm and actuator, a return spring connected with one of the spacing levers, and a stop on the main frame arranged to be engaged by one of the spacing levers to determine the normal position of the space bar and actuator.

15. In a typewriting machine, the combination of a shiftable frame part, a platen carriage and dog rocker on said shiftable frame part, an upstanding dog rocker actuator pivotally held to said shiftable frame part at its lower end to swing fore and aft of the machine and engaging behind the dog rocker at its upper end, shift-key-operated means for elevating the shiftable frame part, a main frame part, a rock shaft journaled on the main frame part, an upstanding rock arm rigidly held to said shaft, a link connecting said arm and actuator adapted to swing vertically during case-shift movements of the shiftable frame part, spacing levers rigidly held to the rock shaft, and a space bar carried by said spacing levers.

16. In a typewriting machine, the com-

bination of a main frame, a platen carriage shiftable in an up-and-down direction to change case, shift-key-operated means for shifting the carriage, printing instrumentalities, a feed-dog rocker mounted to partake of the case-shift movements of the carriage, two independent pivotally supported dog-rocker actuators also mounted to partake of the case-shift movements of the carriage, each of said actuators loosely engaging the dog-rocker to operate the rocker without moving the other actuator, a universal bar controlled by the printing instrumentalities operatively connected to swing one of said actuators in all case positions of the carriage, a space bar, a swinging member operable by the space bar, and a link extending fore and aft of the machine pivotally connected at its ends to said member and the other dog-rocker actuator, said universal bar and the space bar and swinging member being mounted on the main frame and said link swinging up and down during case-shift movements of the carriage.

17. In a typewriting machine, the combination of a case shift frame for a platen carriage, rack and dog escapement mechanism shiftable with said frame, a pair of independent actuators for the escapement mechanism shiftable with the shift frame, independent space-key and character-key controlled devices on the main frame of the machine each connected with a different one of said actuators for operating its associated actuator alone.

18. In a typewriting machine, the combination of a case shift frame for a platen carriage, rack and dog escapement mechanism shiftable with said frame, a pair of independent actuators for the escapement mechanism shiftable with the shift frame, independent space-key and character-key controlled devices on the main frame of the machine each connected with a different one of said actuators for operating its associated actuator alone, each of said actuators being arranged to loosely engage a part of the escapement mechanism and shift the same without transmitting motion to the other actuator.

19. In a typewriting machine, the combination of a case shift frame for a platen carriage, rack and dog escapement mechanism shiftable with said frame, a pair of independent actuators for the escapement mechanism shiftable with the shift frame, independent space-key and character-key controlled devices on the main frame of the machine each connected with a different one of said actuators for operating its associated actuator alone, said actuators loosely engaging a pivoted controlling element of the escapement at opposite sides of said element and at opposite sides of the pivotal axis of the element.

20. In a typewriting machine, the combination of a main frame, a platen carriage, a shift frame supporting said carriage, mechanism for case-shifting the shift frame, a carriage escapement partaking of case-shift movements of the carriage, universal bar mechanism for actuating the escapement including a part mounted on the shift frame and arranged to engage a part of said shift frame to determine the normal position of the parts of said universal bar mechanism, and space bar mechanism for actuating the escapement independently of the universal bar mechanism and including a part mounted on the main frame and arranged to engage a part of the case shift mechanism for determining the normal position of the parts of said space bar mechanism.

21. In a typewriting machine, the combination of a case shift mechanism including a key-operated rock shaft for transmitting motion to the part to be shifted, a space bar supporting lever, and a return spring for said lever normally rocking the lever into engagement with said rock shaft.

22. In a typewriting machine, the combination of an escapement actuator, a space bar, means forming an operating connection between said bar and actuator, a case-shift mechanism including a key-operated rock shaft, and a return spring arranged to normally urge a part of the connecting means into engagement with said shaft, whereby said shaft acts as a stop to determine the normal positions of the space bar and actuator.

23. In a typewriting machine, the combination of a main frame, a platen carriage, a case shift frame upon which said carriage is mounted, an escapement for the carriage including a dog rocker pivotally supported on the shift frame, ribbon vibrating means shiftable with the carriage, printing instrumentalities, a universal bar mounted on the main frame and operable by the printing instrumentalities, an actuator mounted on the shift frame for actuating the dog rocker and ribbon vibrating means, a space bar supported on the main frame, a second actuator mounted on the shift frame for actuating the dog rocker without imparting movement to the ribbon vibrating means and universal bar, said actuators being supported wholly on the shift frame for movement bodily with said frame, operating means connecting the universal bar with the first mentioned actuator in all case positions of the shift frame, and operating means connecting the space bar with the second actuator in all case positions of the shift frame.

24. In a typewriting machine, the combination of a carriage escapement, a pivot member, an escapement actuating lever having an open pivot bearing through which said pivot member extends, a part having a

fixed relation with said pivot member, said lever having a slot therein extending in the direction of its pivotal motion, and a retaining device detachably held to said part having a shank extending through said slot and having a head co-operating with said part to prevent lateral movement of the lever, the shank of said retaining device serving to

prevent movement of the lever in a direction permitting passage of the pivot member through the open side of the pivot bearing in the lever. ¹⁰

In testimony whereof I hereunto affix my signature.

HENRY ALLEN AVERY.
